Inventor.

Marion Jacobs.

UNITED STATES PATENT OFFICE.

MARION JACOBS, OF STURGIS, MICHIGAN.

CAR-COUPING.

SPECIFICATION forming part of Letters Patent No. 276,183, dated April 24, 1883.

Application filed August 21, 1882. (No model.)

To all whom it may concern:

Be it known that I, MARION JACOBS, a citizen of the United States, residing at Sturgis, county of St. Joseph, and State of Michigan, 5 have invented certain new and useful improvements in a link-guide of great value in coupling railroad-cars; and I do hereby declare that the following is a full, clear, and exact description of the invention, which will enable 10 others skilled in the art to which it appertains to make and use the same.

The object of my invention is to furnish a device which will enable a human being to perform the act of coupling cars with the ordinary link and pin without the hazardous exposure 15 of life and limb by being compelled to place himself between the rails and in front of the car and guide the coupling-link with his hand. In order to accomplish this object I journal to 20 the end of the car a rod with its ends bent forward to form angular levers, and then bent inward and connected by a chain, forming a flexible loop to receive and guide the link when the device is elevated by an operator, who may 25 stand outside of the railroad-rails.

On reference to the drawings annexed it will be understood how the invention can be carried into practical effect, similar letters of

reference being marked on corresponding parts on all the figures alike.

Figure 1 represents a perspective view; Fig. 30 2, a front elevation of the device.

A will represent the end of the car, to which the rod C is journaled, with ends bent forward to form angle-levers for rotating, and then bent 35 inward and connected by the chain-loop E at the ends D.

B will represent the ordinary link-and-pin coupling attached to car A, and F the journals securing the rod C to the end of the car A. 40

Now, having fully described my invention, what I claim, and desire to secure by Letters Patent, is—

The rod C, journaled to the end of the car, 45 its ends bent forward to form angle-levers for rotating the rod, and then bent inward, and being connected at the ends D by the chain E, forming a flexible loop, for the purpose described and specified.

In testimony that I claim the foregoing as 50 my own I affix my signature in presence of two witnesses.

MARION JACOBS.
